(57) **CLAIM**

The ornamental design for a pear cut precious stone, as shown and described.

DESCRIPTION

FIG. 1 is a perspective view of a pear cut precious stone, showing my new design.

FIG. 2 is another perspective view of the pear cut precious stone of FIG. 1.

FIG. 3 is a top view of FIG. 1.

FIG. 4 is a bottom view of FIG. 1.

FIG. 5 is a front view of FIG. 1.

FIG. 6 is a rear view of FIG. 1.

FIG. 7 is a left side view of FIG. 1, the right side being a mirror image thereof.

FIG. 8 is a perspective view of a pear cut precious stone, showing my design with a smooth continuous girdle surface.

FIG. 9 is a top view of FIG. 8.

FIG. 10 is a bottom view of FIG. 8.

FIG. 11 is a front view of FIG. 8.

FIG. 12 is a left side view of FIG. 8, the right side being a mirror image thereof; and,

FIG. 13 is a left side view of FIG. 8, with the right side view being symmetrical.
